CASING FOR A TEACHING MACHINE

John C. L. Leslie, Albuquerque, N. Mex., assignor to Educational Research Associates, Inc., Albuquerque, N. Mex., a corporation of New Mexico

Filed Sept. 30, 1965, Ser. No. 87,236

Term of patent 3½ years

(Cl. D25—1)

FIG. 1

FIG. 2

FIG. 3

FIGURE 1 is a perspective view of a casing for a teaching machine showing my new design;

FIGURE 2 is a side view of the teaching machine; and

FIGURE 3 is a front view of the teaching machine. The dominant features of my design reside in the full line portions shown.

I claim:

The ornamental design for a casing for a teaching machine, as shown and described.
